UNITED STATES PATENT OFFICE.

PETER M. KLING, OF ST. LOUIS, MISSOURI.

LACING ATTACHMENT.

SPECIFICATION forming part of Letters Patent No. 658,952, dated October 2, 1900.

Application filed March 30, 1900. Serial No. 10,735. (No model.)

To all whom it may concern:

Be it known that I, PETER M. KLING, a citizen of the United States, residing at the city of St. Louis, in the State of Missouri, have invented certain new and useful Improvements in Lacing Attachments, of which the following is a full, clear, and exact description, reference being had to the accompanying drawings, forming part of this specification.

10 My invention relates to an attachment for leggings, corsets, gloves, or other articles to receive the lacing-cord and by the use of which a pull on the free end of the lace will cause the leggings to be tightened up throughout 15 the entire length of the laced part.

My invention consists in features of novelty hereinafter fully described, and pointed out in the claims.

Figure I is a perspective view showing a 20 legging with my attachment applied. Fig. II is an enlarged view of one of the attachments. Fig. III is a section taken on line III III, Fig. II. Fig. IV is an enlarged view showing two 25 of the attachments in section, the section being taken just beneath the heads of the attachments.

1 represents a legging to which I have shown my invention applied, although it may be used on other garments or articles.

30 The attachment consists of an attaching base or plate 2, upon which is cast or formed a neck 3, having an overhanging head 4, conforming to the contour of the neck.

5 is a lace or cord that bears against the 35 neck of the attachment beneath the head 4. The neck of each attachment is made of more than half a circle, so that the cord does not come against the corners or edges 6.

The attachments are secured to the garment 40 by rivets 7. To prevent the lace or cord from being disengaged from the attachments, the heads 4 are joined to the plates 2 by narrow extensions 8, of reduced dimensions, in the di-

rection of the circumference of the neck, that extend from the heads to the plates, thus 45 forming an eye of reduced thickness at the back of the neck.

When the garment is laced up, a pull on the free end of the lace will cause the garment to be tightened up throughout the extent of the 50 laced portion, the cord passing through the attachment freely and easily, much in the same manner that it would were the attachment composed of a series of pulleys.

I claim as my invention—

1. A lacing attachment comprising an attaching-base, a neck projecting from said attaching-base and having a rounded bearing-surface for the lace, a head conforming to the rounded bearing-surface and overhanging the 60 latter so as to retain the lacing thereon, and an extension of reduced dimension in the direction of the circumference of the neck, extending from the overhanging head to the attaching-base and preventing the disconnection 65 of the lacing-cord with the lacing attachment; substantially as herein set forth. 55

2. In a lacing attachment, the combination of a plate, a neck having a rounded bearing-surface of more than half a circle, a head over- 70 hanging the neck, and a projection joining the head to the plate, substantially as set forth.

3. A lacing attachment comprising an attaching-base, a rounded neck projecting integrally therefrom, a head integral therewith, 75 conforming to, and overhanging the neck, and a reduced extension between an intermediate point on the periphery of the overhanging head and a point in the attaching-base, integral with said parts and forming a reduced 80 eye at the back of the neck; substantially as set forth. 70

PETER M. KLING.

In presence of—

E. S. KNIGHT,
M. P. SMITH.
